DESIGN FOR A LAMP FOR A RANGE

John D. Coleman, Detroit, Mich., assignor to The
Aviation Corporation, New York, N. Y., a cor-
poration of Delaware

Application June 4, 1945, Serial No. 119,887

Term of patent 14 years

(Cl. D48—20)

To all whom it may concern:

Be it known that I, John D. Coleman, a citizen of the United States, residing at Detroit, in the county of Wayne, and State of Michigan, have invented a new, original, and ornamental Design for a Lamp for a Range, of which the following is a specification, reference being had to the accompanying drawings, forming a part thereof.

In the drawings:

Fig. 1 is a front perspective view of a lamp for a range showing my new design, the back portion

of a range being indicated by dot and dash lines for illustrative purposes only;

Fig. 2 is a front elevational view;

Fig. 3 is a side elevational view; and

Fig. 4 is a horizontal sectional view taken on the line 4—4 of Fig. 2.

Fig. 5 is a back elevational view.

I claim:

The ornamental design for a lamp for a range, substantially as shown and described.

JOHN D. COLEMAN.
